UNITED STATES PATENT OFFICE.

GEORGE SARDOU, OF NEW YORK, N. Y.

FOLDING BOX.

Application filed March 9, 1922. Serial No. 542,241.

To all whom it may concern:

Be it known that I, GEORGE SARDOU, a citizen of the United States of America, and resident of the borough of Manhattan, city, 5 county, and State of New York, have invented certain new and useful Improvements in Folding Boxes, of which the following is a specification.

My invention relates to folding boxes generally constructed of cardboard or the like, and has for its object to provide a box of this type which is economical to construct and which may readily be set up to constitute an efficient and reliable container. A 10 further object of my invention is to construct the box in a novel and special manner to serve as a container for predetermined articles and to provide individual compartments for the accommodation of the articles in 15 question. Other more specific objects of my invention will appear from the description hereinafter, and the features of novelty will be pointed out in the appended claims.

In the accompanying drawings, which 20 illustrate an example of the invention without defining its limits, Figure 1 is a face view of the blank from which the box is constructed; Fig. 2 is a plan view of the box set up and with the cover in an open position; Fig. 3 is a longitudinal section on the line 3—3 of Fig. 2, and Fig. 4 is a cross-section on the line 4—4 of Fig. 2.

For the purposes of illustration and description, I have chosen a folding box of 25 distinctive form, designed more particularly to contain a plurality of approximately cylindrical articles such as the collapsible tubes in which creams and pastes are marketed, and adapted particularly to contain a set of tubes of face creams associated with 30 one another, for instance, in the treatment of the human face. It will be understood that this is only an example which is not to be construed as defining the limits of the 35 invention or its field of usefulness.

As shown in Fig. 1, the blank from which the box is constructed comprises a cover panel 10 and a bottom panel 11 connected together in end-to-end relation by means of 40 an end panel 12 and foldable relatively thereto on score lines 13 and 14 respectively. In the illustrated example, the panels 10 and 11 taper toward the end panel 12 whereby the box, when set up for use, is given a distinctive shape and is of less width at one 45 end than at the other; this, of course, is not

an arbitrary requirement, as obviously the panels 10 and 11 may be otherwise shaped than as shown. The cover panel 10 is provided at its opposite longitudinal edges with side flaps 15 and at its free end with an end flap 16, said flaps being foldable relatively to said panel on score lines 17 and 18 respectively, which, with the score line 13, define the periphery of the cover panel 10.

At the end opposite to that at which the end panel 12 is located, the bottom panel 11 is provided with a second end panel 12^a foldable relatively to said bottom panel 11 on a score line 19 and itself provided with an auxiliary end panel 20 foldable on a score line 21; the auxiliary end panel 20, in turn, is continued in the form of a flap 22 foldable on a score line 23.

Side tongues 24 and 25 project in opposite directions from the end panels 12 and 12^a respectively, and are foldable on score lines 26, said tongues 24 and 25, when the box is set up, extending toward each other in registry with the side edges of the panel 11, as will appear more fully hereinafter. The tongues 24 and 25 are preferably of such length as to overlap each other when the box is set up or to abut, although it will be understood that the dimensions of said tongues, as to length, are capable of variation within the limits of the box without destroying their operative functions.

Main side panels 27 and 28 are located along opposite longitudinal sides of the bottom panel 11 and are foldable relatively thereto on score lines 29 which, with the score lines 14 and 19, define the periphery of said bottom panel 11; the side panels 27 and 28, in turn, are continued in the form of auxiliary side panels 30 and 31, foldable on score lines 32. The side panels 27, 28, 30 and 31 constitute the longitudinal side walls of the box when the latter is set up and serve further to lock the tongues 24 and 25 in place, whereby the end panels 12 and 12^a are fixed in position to form the opposite end walls of said box, as will appear more fully hereinafter. The auxiliary side panel 30 is provided with a flap 33 foldable on a score line 34 and adapted to lie in surface engagement with the bottom panel 11 in the operative condition of the box, as shown in Fig. 4. An auxiliary bottom panel 35 forms a continuation of the auxiliary side panel 31 and is foldable relatively thereto on a score line 36, said auxiliary bottom panel

35 being arranged, when the box is set up, to lie upon and over the bottom panel 11. One of the novel features of the improved box resides in the provision of means where-
5 by individual compartments or recesses are defined in the body of the box, this result be-
ing attained by providing flaps capable of being brought to upright positions with re-
spect to the bottom of said box. In the
10 drawings, by way of example, two such flaps 37 are shown, said flaps initially comprising parts of the auxiliary bottom panel 35 and being cut therefrom, as shown in Fig. 1; the flaps 37 remain in connection
15 with said bottom panel 35 along one edge, and are foldable relatively thereto on score lines 38 which define said edge.

In setting up the box for use, the end panels 12 and 12^a are folded upon the lines
20 14 and 19 respectively, to upright positions with respect to the bottom panel 11, and the auxiliary end panel 20 is folded downwardly and inwardly on the line 21 into surface en-
gagement with the inner surface of the end
25 panel 12^a, the flap 22 being folded on the line 23 to lie in surface engagement with the bottom panel 11. The side tongues 24 and 25 are now folded inwardly on the lines
30 26 into registry with the score lines 29 and so as to project toward each other in pairs from the opposite end panels 12 and 12^a; as previously stated, the tongues 24 and 25 preferably are long enough to overlap and thereby become locked in surface engage-
35 ment with each other, or they may terminate at a distance from each other or abut, the dimensions of said tongues being capable of variation without destroying the functional operation thereof.

40 The main side panel 27 is now folded upwardly on the line 29 into surface engagement with the outer surfaces of the tongues 24 and 25 on that side of the box, and the auxiliary side panel 30 is folded down-
45 wardly on the line 32 over and into surface engagement with the inner surfaces of said tongues 24 and 25; the flap 33 is folded on the line 34 into contact with the bottom panel 11 and preferably, at its one end, lies over and in contact with the flap 22. The main side flap 28 is now similarly folded on the line 29 into an upright position in engagement with the outer surfaces of the
50 tongues 24 and 25 and the auxiliary side flap 31 is folded downwardly on the line 32 over and into engagement with the inner surfaces of said tongues 24 and 25 at this side of the box; in this position of the parts, the auxiliary bottom panel 35 folds on the
55 line 36 into engagement with the bottom panel 11 and so as to lie above and extend over the flaps 22 and 33.

When thus set up, the tongues 24 and 25 extend between and are held by the side
60 panels 27-30 and 28-31 respectively, and

thereby fix the end panels 12 and 12^a-20 firmly in upright positions. At the same time, the auxiliary bottom panel 35 maintains the side panels 28-31 in an upright position and by pressure upon the flap 33, fixes the side panels 27-30 in place, the action of said auxiliary bottom panel 35 upon the flap 22 serving also to maintain the auxiliary end panel 20 in its intended position. The end and side walls of the box defined by the panels 12-12^a-20 and 27-30 and 28-31 respectively, are thus of the rigidity required in a box of the type in question and together with the bottom panels 11 and 35 constitute the body of said box. The weight of the contents of the box exerted upon the auxiliary bottom panel 35 prevents any distortion of the box by clamping the flaps 22 and 33 beneath said auxiliary bottom. By folding the flaps 37 up-
65 wardly on the lines 38 to upright positions, a plurality of compartments or recesses 39 are defined within the body of the box and provide independent spaces for the reception of individual articles such as, for instance, tubes of creams or pastes. For instance, the compartments 39 may contain tubes of different creams constituting a set and adapted for facial application, it being understood that the arrangement is preferably such that said articles fit said compartments and are held therein against unintentional removal. The box, with its contents, may thus be set up in advantageous display positions without danger of the articles falling therefrom, and at the same time provides for the individual positioning of the various articles comprising the contents, whereby each article is rendered easily removable independently of and without disturbing any of the others.

70 To close the box, the cover panel 10 is folded on the line 13 over and into registry with the body of the box, the side flaps 15 and end flap 16 being folded on the lines 17 and 18 respectively, and inserted into said body inside of the side walls and one end wall thereof. It will be understood that the location and arrangement of the various panels with respect to each other and relatively to the main bottom panel may be different from that illustrated, without affecting the efficiency of the box.

75 The box provides an efficient and attractive container which may be constructed in a variety of distinctive shapes and which is economical to produce and easily set up for use. Because of its foldability, the box may be stored and shipped in large quantities in a minimum of space, and is also capable of being printed upon and mechanically embellished without difficulty. While I have shown and described the box as being specially adapted for containing articles in the form of tubes, it will be understood that this

is only an example, and that said box is capable of use with equal efficiency in connection with other merchandise.

Various modifications in the specific form shown and described may be made within the scope of the claims without departing from the spirit of my invention.

I claim:

1. A folding box consisting of a body having a main bottom, a single ply end wall, a double ply end wall, double ply side walls all folded relatively to said bottom to operative positions, an auxiliary bottom foldably connected with one side wall and lying over said main body to lock said end and side walls in operative position, a pair of flaps comprising integral parts of said auxiliary bottom and foldable relatively thereto to spaced perpendicular positions to divide said body into a plurality of individual compartments, a cover foldably connected with said single ply end wall and movable to open and closed positions and end and side flaps foldably connected with said cover and adapted in the closed position of the latter, to extend into said body.
2. A folding box comprising a main bottom panel, end panels foldably connected therewith to form the ends of the box,

tongues foldably connected with said end panels and extending toward each other in pairs, main side panels foldably connected with said main bottom panel and arranged to lie against said tongues on the outside, auxiliary side panels foldably connected with said main side panels and arranged to fold over and against said tongues on the inside, an auxiliary end panel foldably connected with one of said end panels and lying against the same from the inside, flaps on said auxiliary end panel and one of said auxiliary side panels adapted to lie against said bottom panel, an auxiliary bottom panel foldably connected with the other auxiliary side panel and arranged to lie upon said main bottom panel and over said flaps, a cover foldably connected with the other end panel, end and side flaps foldably connected with said cover and arranged, in the closed position of the latter, to extend into said box, and flaps comprising integral parts of said auxiliary bottom panel and foldable relatively thereto to spaced, perpendicular positions to divide said box into a plurality of individual compartments.

In testimony whereof I have hereunto set my hand.

GEORGE SARDOU.
